UNITED STATES PATENT OFFICE

2,247,982

ROAD GRADER

Franklin E. Arndt, Galion, Ohio, assignor to The
Galion Iron Works & Manufacturing Company,
a corporation of Ohio

Application December 20, 1939, Serial No. 310,153

17 Claims. (Cl. 37—156)

My invention relates to road graders, and one of its objects is the provision of improved and efficient means for adjusting the moldboard of a road grader from a position under the machine to a steep bank-cutting position at one side of the path of travel of the machine.

More particularly it is the object of the present invention to provide improved and efficient mechanical means operable from the operator's station for adjusting the moldboard of a road grader in elevation and transverse inclination and to laterally shift the positions of the moldboard for the purpose of carrying on road grading operations or bank-sloping operations.

Another object of the invention is the provision of improved and efficient laterally shifting mechanism for a road grader comprising an arcuate rack guided along the arc of a circle surrounding the frame of the machine, combined with drawbar lifting hangers individually operable and each operable independently of the arcuate rack.

A further object of the invention is the provision of laterally shifting mechanism comprising an annular rack surrounding the frame of the machine and connected by a link to the drawbar of the road grader, combined with extensible hangers connected to the drawbar and means for individually actuating the hangers and means for independently rotating the annular rack.

Another object of the invention is the provision in a road grader of laterally shifting mechanism connected to the drawbar of the machine and comprising a circular rack surrounding the frame of the machine, combined with spaced-apart extensible hangers connected to spaced-apart longitudinal rock shafts so located as to be cleared by the latterly shifting mechanism when the latter co-operates with the actuation of the hangers to move the moldboard to an upright bank-cutting position at either side of the machine.

Other objects of the invention will appear hereinafter, the novel features and combinations being set forth in the appended claims.

In the accompanying drawings,

Figs. 1 and 2, placed end to end, represent an elevation of the road grader embodying my improvements;

Figs. 3 and 4, placed end to end, show a plan view of the road grader shown in elevation in Figs. 1 and 2;

Fig. 5 is an enlarged sectional elevation of an intermediate portion of the machine including the annular rack encircling the main frame;

Fig. 6 is a cross-sectional elevational view taken on the line 6—6 of Fig. 2, looking forward in the direction of the arrows, with the moldboard in road grading position;

Fig. 7 is a sectional elevational view looking forward in the direction of the arrows on the section line 6—6 of Fig. 2 but with the moldboard in upright position and the rear wheel structure shown in dotted lines for diagrammatic illustrative purposes;

Fig. 8 is a rear view of the machine with the moldboard in bank-sloping position and the rear wheels adjusted for cutting operations along one wall of a ditch at one side of the roadway; and

Fig. 9 is a view similar to Fig. 6 except that the moldboard is extended laterally to a maximum extent; and

Fig. 10 is a sectional plan view taken on the line 10—10 of Fig. 5.

The machine shown in the accompanying drawings comprises a vehicle frame 12 mounted on the front steering wheel unit 13 and the rear wheels 14, 14 as shown in Figs. 1, 2, 3, 4. The front wheels 15, 15 and the rear wheels 14, 14 are preferably of metal comprising radial spokes and circular rims having circular edges on opposite sides adapted to dig into the ground when leaned as hereinafter more fully described.

As shown in Figs. 1 and 2, the main frame 12 is upwardly arched and is composed of two longitudinal channel beams 16, 16 with their upper and lower flanges extending toward each other and welded together to form a box-like structure, as shown in Figs. 6 and 7. The rear ends of the channel beams 16, 16 are spread apart in diverging relation as shown at 16', 16' in Fig. 4, and these diverging extensions slope downwardly as shown in Fig. 2.

As shown in Fig. 1, the forward end of the main frame 12 is rigidly connected, preferably by welding, to the upright post 17 the lower end of which is mounted by means of the ball and socket joint 18 on the yoke or bolster 19 rigidly connected to an axletree 20 of the front steering wheel unit.

The front wheels may be provided with mechanism for leaning the same and such mechanism may be actuated by means of the crank 21 through the rock shafts 22, 23, 24, 25 connected together by universal joints as shown in Figs. 1 and 2.

The accompanying drawings illustrate a pull type of grader having a vehicle tongue 26, secured by means of a plate 27 to the vertical post 28, the upper end of which is journaled at 29 to the front side of the bolster 19, the lower end of the

post 28 being journaled at 30 to the front axle-tree 20 as shown in Fig. 1.

As shown in Figs. 1 and 3, worm gear mechanism 31 is mounted on the tongue 26 and connected to a sprocket 32 which meshes with a chain 33, the ends of which are connected to the links 34 and 35. The rear ends of these links are pivoted at 36, 37 to the axletree 20. Steering may be effected by turning the wheel 38 at the operator's station shown in Fig. 2, this wheel being connected by means of the rock shafts 39, 40, 41 and 42 to the worm gear mechanism 31. The rock shaft 39 is journaled in the bearings 43, 44 pivoted respectively at 45, 46 to the supporting posts 47, 48 as shown in Fig. 2.

The rock shaft 41 is mounted on the plate 49 which is pivoted at 50 to the upper end of the post 51 which extends upwardly from the post 17. The lower end of the plate 49 is connected by means of a counterbalancing spring 52 to the hook 53 secured to the tongue 26 intermediate the ends thereof, as shown in Fig. 1.

Secured rigidly to the rear ends of the longitudinal beams 16, 16 is a cross-supporting structure 54 (Fig. 2), comprising the angle irons 55, 55 (Fig. 8) which co-operate with means for guiding the rear end of the main frame along the rear axletree 56. By means of a crank 57 connected to gearing in the housing 58, the rock shafts 59, 60 may be actuated to operate mechanism for shifting the rear end of the main frame along the axletree 56.

Mechanism for leaning the rear wheels 14, 14 may be actuated by means of the crank 61 connected to the gearing in housing 62 for actuating the rock shafts 63, 64 and thereby operate the gearing 65 to shift laterally the cross-piece 66, the latter being connected to the upper end of the arms 67, 68 which are secured to the rear wheel axles.

The leaning of the rear wheels may conform to the leaning of the front wheels. Therefore when the moldboard is in road grading position inclined relative to the line of draft, the leaning of the rear wheels cooperates with the leaning of the front wheels and the steering of the front wheels, to counteract the tendency of the moldboard to shift the whole machine toward that side where the front end of the moldboard is located. The shifting of the rear end of the main frame by means of the crank 57, relatively to the rear wheels, enables the rear wheel at the operating side of the machine to be kept in alignment with the front wheel at the operating side of the machine.

Referring now to the road-working implement comprising a moldboard or a scraper blade 69 and the structure for supporting the same, it will be seen that the supplemental frame 70 constitutes a drawbar for the moldboard 69. This supplemental frame or drawbar is a rigid structure relatively narrow and elongated throughout most of its length, particularly at its forward end portion, to facilitate its movement laterally of the narrow elongated main frame, when the moldboard is shifted from road grading position to steep bank-cutting position at one side of the machine, as illustrated in Fig. 8. By referring to Fig. 3 of the drawings it will be seen that the forward portion of the supplemental frame 70 converges or tapers toward the post 17.

While the main frame is upwardly arched to provide ample room for the drawbar and moldboard in their various positions of adjustment, the drawbar is so shaped as to have its rear end

portion approximately horizontal when the moldboard is in road grading position. The intermediate portion of the drawbar is inclined upwardly and forwardly, as shown in Figs. 1 and 2, placed end to end. The forward end portion of the drawbar is preferably horizontal, as shown in Figs. 1 and 2, when the moldboard is in road grading position at the road surface.

As shown in Fig. 1, the forward upper edges of the supplemental frame 70 are inclined downwardly and forwardly at 71. It should be understood that the main frame and the drawbar are thus especially shaped to facilitate movement of the moldboard to the upright bank-cutting position shown in Fig. 8.

The supplemental frame or drawbar 70 comprises spaced-apart angle irons 72, 72' connected by the transverse bracing tubes 73, 74, the ends of which are welded to the angle irons 72, 72'.

20 Welded between the forward ends of the angle irons 72, 72' is a longitudinally extending tubular socket 75. As shown in Fig. 1, an eye-bolt 76 is adapted to be swiveled to the front end of the drawbar having its screw-threaded rod 77 extended through the socket 75 and secured in place by the nut 78. A horizontal U-bolt 79 extends through the eye-bolt 76, as shown in Fig. 1, and this U-bolt extends through openings in the laterally extending brackets 80 and is held rigidly

30 connected to the vertical post 17 by means of the nuts 81. The rear side of the post 17 has a semi-circular recess for receiving the forward end of the eye-bolt 76, but it should be understood that while the U-bolt 79 occupies a horizontal plane

35 and the eye-bolt 76 occupies a vertical plane, a universal connection is afforded to the extent that the eye-bolt may be moved laterally on a vertical pivot relatively to the U-bolt 79 and also vertically on a horizontal pivot relatively to the U-bolt 79. By reason of the universal connection

40 between the front end of the drawbar 70 and the post 17, the front end of the drawbar may be swung laterally and vertically and also rotated in either direction on the axis of the bolt 77.

45 To the rear ends of the heavy structural angle irons 72, 72' is welded the cross-piece 82. To the outer ends of the cross-piece 82, are welded the longitudinally extending tubular sockets 84, 85. The socket 84 is adapted to receive the neck of

50 a spherical head which is adapted to serve as the ball of the ball and socket joint 86 at the lower end of an extensible hanger, as hereinafter fully explained.

The socket 85 is adapted to receive at its ends 55 the necks of spherical heads or balls of the ball and socket joints 87 and 88 as shown in Fig. 4. The ball and socket joint 87 is adapted to serve as the connection to the lower end of another extensible hanger at the opposite side of the machine.

The ball and socket joint 88 is adapted to serve as the connection for one end of the laterally shifting link 89, as hereinafter fully explained.

65 By means of suitable guiding mechanism mounted on the lower sides of the angle irons 72, 72' and the cross-piece 82, the circle 90 is mounted for rotation on an axis at right angles to the drawbar frame 70. The circle 90 has secured thereto supporting framework 91 for mounting the moldboard 69 on the circle 90 to rotate bodily therewith.

The circle 90 is provided with an arcuate rack 92 with which meshes a pinion 93 at the lower end of a shaft adapted to be driven by worm gearing in the housing 94.

The pinion 93 is provided with a ratchet wheel 95 and associated with this ratchet wheel is latch mechanism 96 which is arranged to be released by pulling the handle 97 shown in Fig. 2. As shown in Figs. 2 and 4, the pull handle 97 is connected by means of the rod 98 to a link 99 which in turn is connected by the slidable rod 90' to the latch mechanism 96. When the pull handle 97 is released the spring 101 will automatically snap the latch mechanism into locking position to prevent rotation of the pinion 93 and therefore when this occurs the circle will be locked in adjusted position with the moldboard at an adjusted angle relative to the line of draft of the machine.

When the handle 97 is pulled to release the latch mechanism 96, the circle 90 may be rotated by rotating the crank 21 after setting the shaft of the same in proper position as to the gearing in the housing 102. This gearing is connected by the rock shafts 103, 104 and 105 to the spur gearing in the housing 106. This gearing is connected by means of the shaft 107 and universal joints to the worm gearing in the housing 94. The worm gearing in housing 94 may be self-locking but I prefer to add the latch mechanism 96 to securely hold the circle 90 and the moldboard 69 in adjusted positions and against movement in either direction during road grading operations.

It should be understood that the gearing in the housing 102 may be of the type illustrated in the patent to me, F. E. Arndt, No. 2,012,463, filed Aug. 26, 1930, for an Improvement in road planer or drag so that when the handle 21 is pushed forwardly or rearwardly the turning of the handle may actuate either the mechanism for turning the circle or the mechanism for the leaning of the front wheels.

Extending laterally from the main frame are brackets 108, 109 spaced above the rear end of the supplemental or drawbar frame, as shown in Figs. 2, 4 and 6. Bolted to the outer ends of the laterally extending bracket arms 108, 109 are the journal boxes 110, 111 as shown in Fig. 6. Spaced-apart longitudinal rock shafts 112, 113 have their forward end portions journaled in the journal boxes 110, 111. Extending radially from the forward ends of the rock shafts 112, 113 are the crank arms 114, 115 which are connected by universal joints 116, 117 to the tubes 118, 119 of the extensible hangers 120, 121 each of which comprises a rod 22 or 123. The rods 122, 123 are slidably entirely through the tubes 118, 119. Each rod has a series of perforations or transverse openings 124, 125 which register with perforations 126, 127 in the tubes 118, 119. A pin passing through registering openings in the tubes and rods holds the hangers at adjusted lengths. The lower ends of the rods 122, 123 are connected by means of the universal joints 86, 87 to the outer end of the cross-piece 82 at the rear end of the drawbar frame.

The rear ends of the rock shafts 112, 113 are journaled in the bearings 128, 129 mounted on the upper ends of standards 130 which in turn are supported on the cross-piece 131 welded to the tops of the diverging beam extensions 16', 16". The rear ends of the rock shafts 112, 113 are connected to worm gearing in the housing 132, 133. Large actuating wheels 134, 135 are connected to the worm gearing in the housing 132, 133. Consequently when the operator stands on the platform 136 at the rear end of the machine he may grasp one wheel 134 with his left hand and the other wheel 135 with his right hand and thus individually rock the shafts 112, 113 to secure

adjustment in elevation and transverse inclination of the moldboard 69.

Counterbalancing springs 137, 138 are connected at their lower ends to the rear end of the main frame as illustrated in Fig. 2, the upper ends of the counter-balancing springs 137, 138 being connected by means of chains 139, 140 which in turn are connected to arcuate segments 141 secured to the rock shafts 112, 113. As shown in Figs. 2 and 4 the counterbalancing springs 137, 138 are so arranged so as to act on the rock shafts 112, 113 to tend to lift the hangers together with the rear end of the drawbar and the circle and moldboard mounted thereon, thus relieving the operator of considerable work in effecting adjustments in elevation of the moldboard.

The laterally shifting mechanism for shifting the moldboard to its maximum extent to one side of the machine as shown in Fig. 9 and the means for shifting the moldboard to the bank sloping positions shown in Figs. 7 and 8, will now be described. As shown in Fig. 4, the laterally shifting link 89 is connected to one end of the cross-piece 82 at the rear end of the drawbar frame by means of the ball and socket joint 88. The other end of the laterally shifting link 89 is connected by a ball and socket joint 142 to the lower end of the arm 143 which extends radially from the ring 144 which is journaled at 145 to a circular guide bearing 145' secured to the channel beams 16, 16' of the main frame 12.

Extending laterally from the channel beams 16, 16' are plates 146, 146' and 147, 147' as shown in Figs. 5 and 10. These plates may be welded to the beams. The guide support 145' for the ring 144 is preferably made in two sections 148, 149 and secured by means of the bolts 150, 151 between the plates 146, 146' and 147, 147' shown in Figs. 5 and 10. The sections 148, 149 are preferably cast in one piece, then broken in two at 152, 153, Fig. 6, and the broken surfaces fitted together before bolting to the plates 146, 147, 146', 147' (Fig. 10).

The ring 144 is also in two sections with their ends provided with radial brackets 154, 155 bolted together with a plurality of shims between the brackets. This arrangement facilitates not only the fitting during assembly but also the fitting of the parts to take up wear. The adjustment to take up wear may be effected by taking out one or more shims between the brackets 154, 154 and 155, 155.

The ring 144 is provided with an inner annular rack 156 with which meshes the pinion 157 at the forward end of the shaft 158 which is journaled in the bearing 159 secured to the underside of the main frame 12, as shown in Fig. 6. The shaft 158 extends rearwardly as shown in Fig. 2 and is connected to worm gearing in the housing 159'. As shown in Fig. 4, a wheel 160 is connected to the worm gearing in the housing 159'. The wheel 160 is located adjacent the operator's station 136 and when this wheel is rotated, the ring 144 may be rotated and thereby effect rotation of the arm 143 and translation of the laterally shifting link 89 to effect lateral shifting of the moldboard.

It should be particularly noted that the arm 143 can move through an angle of approximately 270°. As shown in Fig. 7, the rock shafts 112, 113 are so far spaced from the ring 144 that not only the arm 143 will clear either rock shaft 112 or 113 but even the laterally

shifting link 89 will have ample clearance when the moldboard is moved to upright position at either side of the machine. In Fig. 7 the hanger 120 is relatively long, whereas the hanger 121 is relatively short. While the hangers 120 and 121 are extensible in length, it is not necessary to have the laterally shifting link 89 adjustable in length. As shown in Figs. 6 and 7 a laterally shifting link 89 of a given length may be used in combination with extensible hangers either for road grading operations at the road surface or for steep bank-cutting positions such as that shown in Fig. 7. That being true with respect to the usual limits of adjustment of the moldboard, it follows that various intermediate adjustments may be made by using the link 89 of a given length and adjusting the lengths of the hangers.

By referring to Fig. 5, it will be seen that a depending bracket 163, secured to the bottom of the box frame 12 is adapted to receive a cap screw 163' which is threaded into the bearing ring 145'. The ring bearing 145' is therefore very securely but detachably secured to the box frame 12 to surround the latter while spaced therefrom.

As shown in Fig. 5 a tube 161 extends downwardly and forwardly through the box frame 12 and through the ring bearing 145' and the ring 144 journaled on such ring bearing. The ends of rock shaft 104 are journaled in the ends of the tube 161. The tube 161 being welded to the box frame 12, the rock shaft 104 is journaled in fixed bearings.

At the upper portion of Fig. 5 the rock shaft 23 is journaled in the bearing 162 at the upper side of the ring bearing 145'. By comparing Figs. 1 and 2 placed end to end, with Fig. 5, it will be seen that the shafts 22, 23 are connected to the mechanism for adjusting the leaning of the front wheels. It will thus be seen that operating mechanism extends from the operator's platform through the gear ring 144 to the circle for unlatching and rotating the same and that operating mechanism also extends from the operator's platform through the gear ring 144 to the front wheel leaning mechanism. The operating mechanism extending from the operator's station to the front wheel steering mechanism clears the top of the ring 144, and the rock shafts 112, 113, are spaced apart far enough to prevent arm 143 on the ring 144 ever striking against the same, even when the moldboard is in the upright position shown in Fig. 7.

By comparing Figs. 6 and 9 it can readily be seen that by removing the pins at 126 and 127 in Fig. 6 and turning the ring gear 144 in an anti-clockwise direction the moldboard may be shifted transversely of the path of the machine. After the arm 114 has been swung into such position that the aperture in the tube 118 will register with next to the last hole in the rod 122, further swinging of the arm 114 may be relied on to aid the arm 143 in moving the moldboard transversely of the roadway or toward the right as viewed in Fig. 6. When the aperture in the tube 119 registers in the last hole in the rod 123, the pin 127 may be reinserted whereupon the worm gearings in the casings 132, 133 and 159' will lock the arms 114, 115 and 143 in adjusted positions and the hangers 120 and 121 will cooperate with the link 89 to lock the drawbar rigidly to the main frame. Therefore the moldboard will be held rigidly connected to the main frame because of the latch mechanism 96.

In order to shift the moldboard to the upright position shown in Fig. 7 from the road-grading position shown in Fig. 6, the pin 127 is left in the position shown in Fig. 6 and only the pin 126 is removed. By turning the arms 143 and 115 anti-clockwise as viewed in Fig. 6, the moldboard may be moved toward the right as viewed in Fig. 6. Before this is done, however, it is desirable to operate the circle operating mechanism to shift the moldboard to the diagonal position shown in Fig. 4.

While the rear end of the moldboard is on road surface and the pin 126 still released the anti-clockwise movement of the arms 143 and 115 may raise the right hand end of the moldboard up off the road surface until the aperture in the tube 118 registers with the last aperture 124 in the rod 122 whereupon the pin 126 may be reinserted and then the final movement of the moldboard may be effected by manipulation of the arms 114, 115 and 143.

It should be particularly noted that the center of rotation of the ring gear 144 is on a center the axis of which extends longitudinally through the upper portion of the main frame 12. The center of rotation of the ring gear 144 is therefore in a relatively high position which enables the radial arm 143 to be moved to the relatively high position shown in Fig. 7, while the length of such arm 143 is such as not only to clear the rock shafts 112 and 113 between which it is movable as shown in Figs. 2, 6 and 9 but also enable the link 89 to clear such rock shafts as shown in Fig. 7. In other words, by elevating the center of rotation of the arm 143 the latter together with the upper end of the link 89 may be moved to such elevated positions as to enable the moldboard to more readily clear the road surface as it is moved from the road grading position shown in Fig. 9 to the upright bank cutting position shown in Fig. 7. By referring to Fig. 7 it can be seen that when an approximate horizontal plane is extended through the rock shafts 112, 113, it will be adjacent the axis of rotation of the gear ring 144 and below the arm 143 and particularly below the upper ends of the arm 143 and link 89. When the arm 143 is moved from the position shown in Fig. 9 to the position shown in Fig. 7, it is projected upwardly through the space between the rock shaft 113 and the gear ring 144; likewise the link 89 is projected upwardly into such space. The high lift of the grader blade from the road surface when the grader blade is to be moved from road grading position under the vehicle frame to bank sloping position at either side thereof is of particular advantage in that it enables a relatively long moldboard to be used.

Whether in the upright position shown in Fig. 6 or in any bank-sloping position between such upright position and road-grading position under the main frame, the moldboard will be held rigidly connected to the main frame in the same manner as above described in connection with the maximum laterally extended position of the moldboard shown in Fig. 9.

In Fig. 9 the right-hand rear wheel is shown in dotted lines designated 14. In such maximum laterally extended position, the circle operating mechanism may shift the moldboard to any desired angle relative to the line of draft. While Fig. 9 shows the moldboard horizontal for horizontally trimming berms or shoulders of roadways the right-hand end of the moldboard as viewed in Fig. 9 may be inclined downwardly

for ditch-work. Adjustments for ditch-work may be made by substituting a longer hanger for the one designated 121 in Fig. 9 and adjusting it to its full length and then release the pin 126, turn the arm 143 anti-clockwise, and finally replace the pin 126 after turning the arm 114 until apertures in the tube 118 and rod 122 register.

When the moldboard is to be shifted to an upright bank sloping position at the left-hand side of the machine or to a position opposite to that shown in Fig. 7, the diagonal link 89 is first reversed by connecting the socket joint 88 to the spherical head which is shown in Fig. 7 projecting from the tubular socket 84. This may readily be done while the moldboard 69 is in the road grading position shown in Fig. 6. The grader blade may then be shifted to its extreme left-hand road grading position opposite to that shown in Fig. 9, when the arm 143 will be at the left of the ring gear 144 as viewed in Fig. 9 and the link 89 will hang vertically with its lower end or socket joint 88 connected to the spherical head projecting rearwardly from the tubular socket 84. In the left-hand upright cutting position of the moldboard the upper end of the link 89 and the upper end of the arm 143 will be located above a horizontal plane extending through the top of the vehicle frame. In both the right-hand upright position of the moldboard and in the left-hand upright position thereof the link 89 will be in suspension. It will thus be seen that the high lift from the road surface may be had preparatory to adjustment of the moldboard to upright bank cutting position at either side of the machine.

It will thus be seen that by the use of mechanism for turning the arm through an angle of at least 270°, in co-operation with extensible hangers the moldboard may be adjusted to upright position on either side of the machine to any bank-sloping position at either side of the machine where the cutting edge of the moldboard will be entirely outside of the path of travel of the machine. Furthermore, a wide range of lateral adjustment of the moldboard is available for shoulder trimming and berm work and even for downwardly sloping ditch-work at the edges of either side of the roadway.

While hangers of extensible lengths are preferable, detachable hangers of fixed lengths may be used throughout a wide range of adjustments by reason of the wide range of adjustment of the ring gear 144 and the arm 143. For instance, if the hanger 121 is of fixed length it can readily be used in co-operation with the link 89 and arm 143 for adjusting the moldboard to a laterally shifted position where the hanger 120 of fixed length may be replaced by another hanger having a fixed length equal to the length of the hanger 120 shown in Fig. 7. Then the moldboard may be adjusted to the upright position shown in Fig. 7.

The flexible connection between the front end of the drawbar 70 and the upright post 17, comprising the eye-bolt 76 and the U-bolt 79, is described and claimed in my co-pending application S. N. 391,369, filed May 1, 1941, for an Improvement in road graders. The curved ends of the arcuate rack with which the pinion 65 meshes as shown in Fig. 8, are shown; fully described and claimed in my co-pending application S. N. 381,857, filed March 5, 1941, for an Improvement in road graders.

Obviously those skilled in the art may make

various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

- 10 1. In a road grader, the combination with a vehicle frame having a laterally expanded rear end portion and a narrow elongated forward portion, of a drawbar pivotally connected at its forward end to the forward end of said frame, brackets extending laterally from the narrow elongated portion of said vehicle frame, crank arms journaled on said brackets on spaced axes, mechanism for actuating said crank arms on such spaced axes, spaced-apart hangers one connected between one crank arm and one side of the free end of said drawbar and the other connected between the other crank arm and the other side of the rear end of said drawbar, an arcuate rack, mechanism mounting said rack on said frame and guiding the same relatively thereto along the arc of a circle surrounding said vehicle frame, mechanism comprising a linking connecting said arcuate rack to one side of the free end of said drawbar, means comprising a pinion meshing with said arcuate rack to move the same arcuately to effect lateral shifting of said drawbar together with the road-working implement carried thereby, and means for actuating said crank arms individually and independently of the actuation of said arcuate rack.
- 15 2. In a road grader, the combination with a vehicle frame, of a drawbar flexibly connected at its forward end to said vehicle frame, a road working implement carried by said drawbar, spaced-apart hangers pivotally connected at their lower ends to said drawbar, spaced-apart rock shafts mounted on opposite sides of said vehicle frame to extend longitudinally thereof, crank arms extending radially from the forward ends of said rock shafts and pivotally connected to the upper ends of said hangers, mechanism connected to the rear ends of said rock shafts to rock the same individually, an arcuate rack, means for guiding said rack along the arc of a circle surrounding said vehicle frame, mechanism comprising a link connecting said rack to one side of the free end of said drawbar, and means for driving said rack arcuately to effect lateral shifting of the drawbar together with said road working implement while the free end of said drawbar is suspended from said vehicle frame by said hangers and radial crank arms.
- 20 3. In a road grading machine, the combination with a vehicle frame, of a drawbar frame, a grader blade carried by said drawbar frame, extensible hangers connected to said drawbar frame, brackets extending laterally from said vehicle frame, crank arms connected to said hangers and mounted on said brackets in spaced relation to the sides of said vehicle frame, mechanism for swinging said crank arms individually on longitudinal axes spaced from the sides of said vehicle frame, a tertiary frame of arcuate shape movable along the arc of a circle which encircles said vehicle frame, bearing means on said vehicle frame supporting said tertiary frame for arcuate adjustment, a rack on said tertiary frame, pinion means co-operating with said rack to adjust the tertiary frame relative to said vehicle frame, and mechanism comprising a link interconnecting

said tertiary frame and said drawbar frame to effect laterally shifting of the grader blade when said tertiary frame is moved arcuately as aforesaid, the construction and arrangement being such that adjusting the hangers to different lengths and actuating the same in co-operation with said lateral shifting the grader blade may be adjusted to bank sloping position at one side of the machine.

4. In a road grader, the combination with a vehicle frame, comprising an elongated box-like portion, of a ring surrounding said box-like portion, a radial arm on said ring, a drawbar flexibly connected at one end to said vehicle frame, a grader blade carried by said drawbar, spaced-apart hangers each extensible in length and each connected to said drawbar, a link connecting said ring to said drawbar, brackets extending laterally from said vehicle frame, crank arms mounted on said brackets and connected to said hangers to swing on longitudinal axes spaced from the sides of said vehicle frame, mechanism for swinging said crank arms individually, and means for rotating said ring around said vehicle frame to effect lateral shifting through said radial arm and said link of the grader blade, the construction and arrangement being such that by adjusting the lengths of said hangers and operating said crank arms and rotating said ring the grader blade may be adjusted to various laterally shifted positions at either side of the machine or to various steep bank sloping positions at either side of the machine including upright positions spaced laterally from either side of the vehicle frame and outside of the path of travel thereof.

5. In a road grader, the combination with a vehicle frame, of a supplemental frame connected thereto, a road working implement carried by said supplemental frame, spaced-apart hangers connected to said supplemental frame, means comprising spaced-apart rock shafts mounted on said vehicle frame for actuating said hangers individually, a ring surrounding said vehicle frame and having an internal gear, a crank arm extending radially from said gear ring, a link connecting said crank arm to one side portion of the free end of said supplemental frame, and mechanism comprising a pinion meshing with said internal gear to effect rotation of the same to laterally shift the supplemental frame together with the road-working implement carried thereby, the construction and arrangement being such that the rock shafts and gear ring may be rotated on different axes and that the hangers may be actuated independently of the crank arm and the latter may be actuated independently of the hangers.

6. In a road grader, the combination with a vehicle frame, of a supplemental frame connected thereto, a grader blade carried by said supplemental frame, a tertiary frame surrounding said vehicle frame, a link connecting said tertiary frame to one side of the free end of said supplemental frame, means for actuating said tertiary frame arcuately to effect lateral shifting of said supplemental frame together with the grader blade carried thereby, extensible hangers one connected to one side of the free end of said supplemental frame and the other connected to the other side of the free end of said supplemental frame, two crank arms one connected to one of said extensible hangers and the other connected to the other extensible hanger, mechanism for supporting said crank arms on said vehicle frame for rotation on spaced longitudinal axes each in

spaced relation to the axis of rotation of said tertiary frame, and mechanism for actuating said crank arms individually but in co-operation with the actuation of said tertiary frame to effect adjustment of the grader blade to steep bank sloping position with the link in suspension.

7. In a road grader, the combination with a vehicle frame, of a drawbar connected thereto, a road working implement carried by said drawbar, means comprising hangers supported by said vehicle frame and spaced laterally from the sides thereof for supporting said drawbar from said frame and for adjustment relative thereto, laterally shifting mechanism between said vehicle frame and said drawbar comprising a ring guided around said vehicle frame on a longitudinal axis spaced from said hangers and having a radial arm connected by a link to one side of the free end portion of said drawbar, said supporting means being separate from said laterally shifting mechanism, and means for actuating said hangers individually on longitudinal axes each spaced apart from the axis of rotation of said ring.

8. In a road grader, the combination with a vehicle frame, of a drawbar flexibly connected at its front end to the front end of the vehicle frame, a mold-board carried by said drawbar, spaced-apart hangers pivotally connected at their lower ends to opposite sides of the free end of said drawbar, actuating arms pivotally connected to said hangers and mounted on said vehicle frame for rotation on spaced-apart axes extending longitudinally of said vehicle frame, mechanism for actuating said arms individually, an annular gear, mechanism on said frame for guiding said annular gear for rotation about said frame on an axis extending longitudinally thereof, a radial arm carried by said annular gear to rotate therewith to various positions between the aforesaid spaced-apart axes to extend laterally from either side of the vehicle frame and to positions above an approximate horizontal plane extending through the said spaced-apart axes, the positions of said radial arm intermediate such laterally extending positions being under the vehicle frame, means for rotating said annular gear to shift said radial arm from one position above such horizontal plane at one side of said frame to another position above such plane at the other side of said frame, and a link connectable to either side of the free end of said drawbar and pivotally connected to said radial arm, said link being in suspension when the moldboard is in steep bank cutting position at either side of the machine.

9. In a road grader, the combination with a vehicle frame, of a drawbar flexibly connected at its forward end to said vehicle frame, a road working implement carried by said drawbar, spaced-apart hangers pivotally connected at their lower ends to said drawbar, spaced-apart rock shafts mounted on opposite sides of said vehicle frame to extend longitudinally thereof, crank arms extending radially from the forward ends of said rock shafts and pivotally connected to the upper ends of said hangers, mechanism connected to the rear ends of said rock shafts to rock the same individually, an arcuate rack, means for guiding said rack along the arc of a circle surrounding said vehicle frame, an arm extending radially from said arcuate rack and movable with the latter to positions on opposite sides of said vehicle frame above a horizontal plane extending through said rock shafts, said arm being movable past the inner sides of said rock shafts, a

link connecting said arm on said arcuate rack to one side of the free end of said drawbar, and means for driving said rack arcuately to effect lateral shifting of the drawbar together with the road working implement carried thereby, such lateral shifting being adapted to co-operate with the actuation of said hangers to adjust the road working implement to upright bank cutting position with said arm above said horizontal plane and said link inside of the adjacent rock shaft without interference with the latter.

10. In a road grader, the combination with a vehicle frame, of a drawbar flexibly connected at its forward end to the front end of said vehicle frame, a moldboard carried by said drawbar, spaced-apart extensible hangers pivotally connected to said drawbar, crank arms pivotally connected to the upper ends of said hangers, rock shafts connected to said crank arms and journaled on said vehicle frame for operation on spaced-apart axes extending longitudinally of said vehicle frame, mechanism for actuating said rock shafts individually to effect adjustment of said crank arms and hangers to change the position of said moldboard relative to said vehicle frame, laterally shifting mechanism comprising an annular gear encircling said frame and connected by a radial arm and a link to said drawbar with the gear guided for projection of one end of said link upwardly through the space between said gear and the adjacent rock shaft, and means for rotating said annular gear in co-operation with the actuation of said hangers to effect adjustment of the moldboard to upright bank cutting position.

11. In a road grading machine, the combination with a vehicle frame, of a drawbar having its forward end flexibly connected to said vehicle frame, extensible hangers pivotally connected to said drawbar, mechanism comprising spaced-apart rock shafts mounted on said vehicle frame and connected to said extensible hangers, an operator's station on said vehicle frame, mechanism for operating said rock shafts individually from said operator's station, an arcuate rack, means for guiding said rack along the arc of a circle surrounding said vehicle frame, the center of such circle being spaced above the bottom of that portion of the frame above the rear end of the drawbar, an arm extending radially from said arcuate rack and movable to positions above a horizontal plane extending through said rock shafts, a link connecting said arm to one side of the rear end of the drawbar, and mechanism operable from said operator's station for moving said rack arcuately along said guiding means to effect adjustment of the moldboard to upright bank cutting position by co-operation with the lengths of the hangers and the individual actuation thereof.

12. In a road grading machine, the combination with a wheel supported main frame, of a drawbar frame flexibly connected thereto, a moldboard carried by said drawbar frame and adapted to occupy a road grading position, extensible hangers connected to said drawbar frame, crank arms supported by said main frame and spaced from opposite sides thereof, said crank arms being connected to said hangers, mechanism for actuating said crank arms on longitudinal axes spaced from opposite sides of said main frame, laterally shifting mechanism comprising an annular gear guided around said main frame and having a radial arm connected by a link to said drawbar frame, said annular gear being movable

through a wide angle of over 180° to project said arm and the upper end of said link above a horizontal plane extending through said spaced axes, a horizontal shaft extending through the rear portion of said main frame, a pinion on the front end of said shaft meshing with said annular gear, and mechanism for rotating said shaft to effect operation of said laterally shifting mechanism in co-operation with the actuation of said hangers to secure adjustment of the moldboard to upright bank cutting position.

13. In a bank cutting machine, the combination with a vehicle frame, of a drawbar flexibly connected thereto, a grader blade carried by said drawbar, rock shafts journaled to said vehicle frame on axes spaced from the sides of the frame, crank arms on said shafts for rotation in planes extending transversely of said vehicle frame, hangers connecting said crank arms to said drawbar, mechanism for actuating said crank arms, an arcuate rack, an arcuate bearing on said main frame for guiding said rack along an arc of a circle surrounding said vehicle frame, the center of such circle being in a relatively high position extending longitudinally through said vehicle frame, a link connecting said arcuate rack to one side of the rear end portion of said drawbar, and mechanism comprising self-locking worm gearing for moving said rack along said arcuate bearing to effect through said link lateral shifting of the grader blade to adjust the latter to steep bank cutting position in co-operation with the actuation of said hangers, the construction and arrangement being such that the upper end of said link may be projected to a relatively high position by reason of the relatively high position of the center of said circle thereby enabling the grader blade to be elevated throughout its length from the road surface sufficiently to clear the latter when such grader blade is being moved from under the vehicle frame to bank cutting position at one side thereof.

14. In a road grading machine, the combination with a vehicle frame, of a drawbar flexibly connected thereto, spaced-apart rock shafts journaled to said frame on spaced-apart axes extending longitudinally of said vehicle frame, extensible hangers pivotally connected to said drawbar, crank arms on the forward ends of said rock shafts and pivotally connected to said extensible hangers, an annular gear, mechanism for guiding said annular gear to rotate around said vehicle frame on an axis extending longitudinally through the upper portion of said frame with the axes of said rock shafts spaced laterally from the axis of rotation of said annular gear, a radial arm on said annular gear and movable with the latter to positions extending upwardly and diagonally outwardly above a horizontal plane extending through said rock shafts, a link connecting said arm to one side of the rear end of said drawbar, an operator's station, mechanism for actuating said rock shafts from said operator's station, and additional mechanism for actuating said annular gear from said operator's station, the construction and arrangement being such that the upper end of said link may be projected above a horizontal plane extending through the top of the machine by reason of the relatively high position of the center of rotation of said annular gear although the said arm is of such length as to enable the outer end thereof and the upper end portion of said link to move past and clear the rock shafts on either side of the machine thereby effecting

sufficient elevation of the grader blade from the road surface to clear the same when being moved to steep bank cutting position at either side of the machine.

15. In a road grader, the combination with a vehicle frame comprising an upper narrow elongated portion, of a ring guided around said upper narrow elongated portion, a radial arm on said ring, a drawbar flexibly connected at one end to said vehicle frame, a grader blade carried by said drawbar, brackets extending laterally from said narrow elongated portion of said frame, spaced-apart rock shafts journaled to said brackets, radial arms on the forward ends of said rock shafts, extensible hangers connecting said radial arms to the free end of said drawbar, a link connecting the first-named radial arm to one side of the free end of said drawbar, mechanism for rotating said ring on a center the axis of which extends longitudinally through said narrow elongated portion of said vehicle frame to move said first-named radial arm and the upper end of said link to positions above a horizontal plane extending through the top of the vehicle frame, and mechanism for actuating said rock shafts individually to enable the hangers, adjusted to different lengths to co-operate with the movement of said link to effect adjustment of the grader blade from road grading position under the vehicle frame to upright bank cutting position at one side of said frame.

16. In a bank cutting machine, the combination with a vehicle frame, of a drawbar flexibly connected at its forward end to said vehicle frame, a grader blade carried by said drawbar, an arcuate rack, means for guiding said rack along an arc of a circle surrounding said vehicle frame in an upright plane fixed relative to said frame, said rack being confined by said guiding means to adjustment in such upright plane, mechanism comprising a suspension link connecting said arcuate rack to one side of the free end of said drawbar, spaced-apart hangers pivotally connected at their lower ends to said

drawbar, mechanism comprising rock shafts mounted on said vehicle frame and spaced laterally from opposite sides of the path of said arcuate rack for actuating said hangers, and

5 means for actuating said arcuate rack to project the upper end of said suspension link upwardly through the space between said path and one of said rock shafts, the construction and arrangement being such that the actuation of said 10 rack co-operates with the actuation of said hangers to effect adjustment of said grader blade to steep bank cutting position while said link remains in suspension.

17. In a road grader, the combination with a vehicle frame, of a drawbar flexibly connected at its forward end to said frame, a grader blade carried by said drawbar, a ring gear, mechanism for guiding said ring gear in a circle surrounding said frame in an upright plane fixed relative to said frame, said guiding mechanism permanently confining said ring gear to adjustment in such upright plane relative to said frame, a radial arm extending from said ring gear, a link connecting said arm to one side of the rear end portion of said drawbar, spaced-apart hangers pivotally connected at their lower ends to opposite sides of the rear end portion of said drawbar, crank arms pivotally connected to said hangers, mechanism mounting said crank arms on said frame for operation on axes extending longitudinally of said vehicle frame and spaced laterally from opposite sides of said ring gear, means for actuating said crank arms individually to secure individual actuation of said hangers, and means for rotating said ring gear to effect lateral shifting of the grader blade, the said crank arms and the mounting mechanism therefor being separate from and independent of the ring gear and the means for rotating the same may be swung transversely of the vehicle frame on the aforesaid longitudinal axes separately from and independently of the longitudinal axis of rotation of said ring gear.

FRANKLIN E. ARNDT.
